UNITED STATES PATENT OFFICE.

JESSE M. PAYNE, OF SUMMERTON, ALABAMA, ASSIGNOR TO PERFECTION DYEING MACHINE COMPANY, OF COLUMBUS, GEORGIA, A CORPORATION OF GEORGIA.

SPREADER ATTACHMENT FOR COLLAPSIBLE BEAMS FOR DYEING-MACHINES.

1,140,283.

Specification of Letters Patent. Patented May 18, 1915.

Application filed October 8, 1914. Serial No. 865,673.

To all whom it may concern:

Be it known that I, JESSE M. PAYNE, a citizen of the United States, residing at Summerville, in the county of Lee and State 5 of Alabama, have invented certain new and useful Improvements in Spreader Attachments for Collapsible Beams for Dyeing-Machines; and I do hereby declare the following to be a full, clear, and exact description of the invention, such as will enable others skilled in the art to which it 10 pertains to make and use the same.

My present invention relates to improvements in dyeing machines, and it especially 15 relates to collapsible beams for such machines, and is intended as an improvement upon the devices shown in the patents to J. M. Payne, No. 1067132 and 1088617, granted, respectively, July 8, 1913, and February 24, 1914, and entitled improvements in 20 dyeing machines.

It is also intended as an improvement upon the devices shown in the patents to J. M. Payne and G. G. Wallace, No. 1053063, 25 granted February 11, 1913, and entitled dyeing apparatus; and No. 1057265, granted March 25, 1913, and entitled improvements in dyeing machines.

In certain of these patents just cited, and 30 in others disclosed in the art, the slats are expanded and contracted by turning screws engaging screw-threads on the spiders or separators, and these screws and screw-threads are immersed in the dye liquor and 35 subsequently subjected to heated air and being permanently inclosed in the warper beam, and more or less inaccessible, become quickly corroded.

According to my present invention the expansion of the slats is accomplished by rotating a nut on the exterior of the warper beam, which by a straight thrust pushes the separators along the engaging wedges and so expands the group of slats, while a reverse movement draws the separators in the 45 reverse direction and permits the tension of the yarn on the slats to cause the compression of the slats.

My invention will be understood by reference to the accompanying drawings, in which the same parts are indicated by the same reference symbols throughout the several views:—

Figure 1 is an end view of the warper

beam as detached from the apparatus; Fig. 55 2 shows a transverse section of the same along the line 2—2 of Fig. 3, and looking in the direction of the arrows; Fig. 3 shows a longitudinal section through the warper beam, parts being shown in elevation, and 60 parts being broken away; and Fig. 4 is a plan view of the device for moving the end separator, and thus expanding the slats to permit the same to collapse, the section through the end separator being along the 65 line 4—4 of Fig. 2 and looking down.

A represents the shaft of the warper beam, on which are mounted the heads B and C, which heads are constructed similar to those shown in my patents aforesaid and 70 form no part of my present invention. On this shaft A are mounted certain fixed spiders D and certain slidable separators E. Extending between the two heads B and C are the slats F, which carry on their inner 75 sides shoes G adapted to engage the spokes of the spiders D when the slats are in the collapsed position, and also shoes H, having wedges or cams h projecting interiorly therefrom, as shown in Fig. 3. These wedges h 80 engage the outer edges of the sliding separators E', which sliding separators are tied together with the rods I, and cottor pins i passing through said rods. These rods I pass freely through the fixed spiders D. 85 The two heads are connected together by a series of tie rods J.

Mounted on the shaft A, and exterior to the warper beam, is a hollow cap K exteriorly screw-threaded as at k, see Figs. 3 90 and 4, and provided with a laterally-projecting lug k', engaging a corresponding groove in the head of the warper beam to prevent this cap from turning relative to said head. The cap is held against longitudinal movement of the shaft A in any convenient way, as by the set screw S engaging the nut T. Engaging these screw-threads k is a hollow nut M, internally screw-threaded, as at m, and provided on its exterior with an annular 100 groove m' to receive the band N, which preferably consists of two halves each having flanges n and connected by the bolts O. Between these flanges n the outer ends of the hooks P are attached, while the inner ends 105 of said hooks are flanged over, as at p, to engage on the inner face of the sliding separator E'. These hook-shaped ends p pass

through the openings e^o in said end separator E' and are locked in engagement with said end separator by the pins p' , so that if these hooks be pressed to the left as shown in Fig. 5 1 the pins p' will force the end separator E' to the left, toward the position indicated in dotted lines in Fig. 3, tending to expand the slats; while if these hooks be pulled to the right they will pull the end separator to the 10 right to the position shown in full lines in Fig. 3, thus permitting the slats to collapse.

The band N is loosely mounted on the nut M, and the turning of the latter nut will move the band and with it the hooks to the 15 right or left, as may be desired. This turning of the nut may be accomplished either by putting a handspike in the opening m^o and turning the same, or by using a wrench on the squared end n^o .

20 When it is desired to disconnect the device shown in Fig. 4 from the warper beam, as would be the case when the yarn is being wound on the warper beam, or after the operation of dyeing has been completed, and 25 it is desired to remove the warper beam from the dyeing vat, it will be sufficient to disengage the set screw S spring up the ends of the hooks P to the position shown in dotted lines in Fig. 4, and then withdraw 30 the entire device shown in Fig. 4 to the right. To return the parts to the initial position, reverse the operation.

It will be seen that the separators E and the end separator E' are bound together by 35 the rods I, and the whole constitutes a spreader frame which may be moved longitudinally in either direction by the nut M, as hereinbefore described. Now in order to hold this spreader frame with the heads in 40 the distended position, against being wedged back longitudinally by the pressure of the yarn as it is being wound on the slats, I provide any suitable locking arrangement such, for instance, as the stop stud Q which 45 is inserted into the head B and bears against the end separator E', as indicated in dotted lines in Fig. 3. When the hooks P are in the engaging position, as shown in full lines in Fig. 3, this stop stud Q may be removed 50 or drawn clear of the path of travel of the end separator E'.

It will thus be seen that I provide a screw and nut engagement exterior to the warper beam by means of which the spreader frame 55 is moved longitudinally in either direction, whereby the slats may be expanded or collapsed, and that this attachment may be readily removed from the warper beam and is readily re-applied thereto when desired. 60 Moreover, it will be noted that there will be only one such attachment required to operate an indefinite number of warper beams, whereas with the devices of the prior art each warper beam carried its own spreading attachment, and this spreading attach- 65

ment was mainly inclosed within the warper beam where it was difficult of access, and consequently difficult of repair, and where the engaging screw-threads were subjected to the corroding effects of the dye liquor.

70 It will be evident that certain of the slats, for instance the alternate slats, may not be provided with the wedge faces h , but simply with the shoes G resting on the ends of the fixed spiders D, while others of the slats, 75 for instance the alternate slats, may be provided with such wedge faces h ; the result would be that when the slat expanding frame is moved longitudinally only the alternate slats would be pressed outward, 80 which construction and its advantages are fully described in my patent, improvements in dyeing machines, No. 1088617, granted February 24, 1914, and hereinbefore referred to.

85 It will be obvious that various modifications might be made in the herein described apparatus and in the construction, combination and arrangement of parts which could be used without departing from the spirit 90 of my invention.

Having thus described my invention, what I claim and desire to secure by Letters Patent of the United States is:—

1. The combination in a hollow warper beam of a central shaft with heads mounted thereon, a plurality of slats extending between said heads and forming the periphery of said warper beam, and mounted to move radially away from the axis thereof, and means for reciprocating said slats outwardly and inwardly away from or toward the axis of said warper beam, said means comprising a series of shoes provided with wedge faces mounted on the inner edges of said slats, a frame provided with a series of separators connected together and adapted to slide relative to said slats and to engage said wedge faces on said shoes, a hollow screw mounted concentric with said shaft and exterior to one of the heads thereof, a hollow nut mounted on said screw, a band loosely mounted on said nut but held against longitudinal movement thereon, and hooks connecting said band and one of said separators, substantially as described.

110 2. The combination in a hollow warper beam of a central shaft with heads mounted thereon, a plurality of slats extending between said heads and forming the periphery of said warper beam, and mounted to move radially away from the axis thereof, and means for reciprocating said slats outwardly and inwardly away from or toward the axis of said warper beam, said means comprising a series of shoes provided with wedge faces mounted on the inner edges of said slats, a frame provided with a series of separators connected together and adapted to slide relative to said slats and to engage said 115 120 125 130

wedge faces on said shoes, a hollow screw mounted concentric with said shaft and exterior to one of the heads thereof, a hollow nut engaging said screw and provided with 5 an annular groove therein, a band loosely mounted in said groove and provided with outwardly-projecting flanges, and hooks connecting said flanges to said frame, with

means for turning said nut, substantially as described.

In testimony whereof I affix my signature in presence of two witnesses.

JESSE M. PAYNE.
